UNITED STATES PATENT OFFICE.

BERNHARD SUCKER, OF WEICHAU, GERMANY.

CHANGEABLE EXHIBITOR.

1,004,931.

Specification of Letters Patent.

Patented Oct. 3, 1911.

Application filed April 5, 1911. Serial No. 619,167.

To all whom it may concern:

Be it known that I, BERNHARD SUCKER, a subject of the King of Prussia, residing at Weichau, in the Kingdom of Prussia, Germany, have invented certain new and useful Improvements in Changeable Exhibitors, of which the following is a specification.

This invention relates to a device which indicates in railway cars at which side the passengers have to get out. It is obvious that such a device is of great practical value as it facilitates the traffic and serves for preventing accidents.

According to the present invention a sign board having the inscription "Get out at this side" is automatically made visible when the train arrives at the station to be automatically removed when the train leaves the station. The shifting of the sign board is effected by means of a mechanism which is operated from an abutment placed on the line under the car against which strikes one of the horizontal arms of a disk. The abutments are removable so that the indicating device is operated only when the train stops at the station. There are two identical devices, arranged in the car one at either side. A bell signal can be connected with the indicating device to attract the attention of the passengers.

In the accompanying drawing the improved indicating apparatus is shown:—

Figure 1 shows diagrammatically the indication device mounted in a railway car. Fig. 2 is a side view of Fig. 1, Fig. 3 shows the sign board.

The mechanism for operating the sign board consists of a vertical disk *q* with horizontal arms *f*. The horizontal axle *c* of the disk is revolvably mounted in a suitable bearing *b* which stands perpendicular to the rails. On the axle *c* a crank *d* is fixed to the upper end *f* of which a push-rod *e* is linked. To the upper end of said push-rod *e* a lever *g* is hingedly connected which is fixed on an axle *h*. Upon the axle *h* a curved board *i* is fixed which has two inscriptions such as for example: "Get out at this side" and a hand pointing in the corresponding direction. The inscriptions are arranged on the upper and on the lower part of said board the middle of which is free. The curved board *i* is inclosed in a

case *k* which has a longitudinal window *l* through which about $\frac{1}{3}$ of the curved board 55 is visible. According to the position of the lever arm *g* the curved board *i* is turned so that the lower inscription, the free middle part, or the upper inscription appears behind the window *l*. At the station an abutment *m* is placed between the rails. One of the horizontal arms *a* of the disk *p* strikes against the abutment *m* whereby the disk is turned through a quarter of a revolution. This revolving motion 60 of the disk is transferred by the crank *d* and by the vertical rod *e* to the lever arm *g* which makes the axle *h* and consequently the curved sign board turn so that it revolves and brings instead of the empty middle space one of the inscriptions behind the window. A signal bell *n* mounted in the car is operated when the curved board *i* revolves. In each car two identical devices are arranged one at either side of the car. 75 The abutment *m* which is removable is placed at the side of the line at which the passengers have to get out.

On the bearing *b* for the axle of the disk *p* with the horizontal arms *a* a blade spring 80 *o* is fixed which is designed to engage with the notches of the disk *p*, so that this disk is secured in its respective position.

I claim:—

An indicating device comprising in combination a casing mounted in the car and having two windows, a curved board at the left hand side of the casing, and a similar board at the right hand side of the casing, an inscription on the upper part 85 of said boards, and a similar inscription on the lower part of said boards, and actuating means for each board comprising a horizontal axle on which said board is fixed said axle being revolvably mounted in the 90 rear wall of said casing, a lever arm fixed to said horizontal axle, a vertical push-rod hingedly connected at its upper end with the free end of said lever arm, a crank arm linked to the lower end of said rod, a bearing 100 fixed under the bottom of the car, a horizontal axle mounted in said bearing its outer end being connected with said crank, a notched vertical disk fixed on the inner end of the horizontal axle, horizontal arms 105 projecting from said notched disk, a blade

spring fixed to said support and engaging with its free end with the notches of said disk, and an abutment removably mounted between the rails so that one of said horizontal arms strikes against the same, substantially as described and shown and for the purpose set forth.

In witness whereof I have hereunto set my hand in the presence of two witnesses.

BERNHARD SUCKER.
